UNITED STATES PATENT OFFICE.

GEORGE W. KNAPP, OF BALTIMORE, MARYLAND, ASSIGNOR TO WM. NUMSEN,
JNO. W. NUMSEN, NATHANIEL G. NUMSEN, AND WM. N. NUMSEN, ALL
OF SAME PLACE.

CHERRY-SEEDED MACHINE.

SPECIFICATION forming part of Letters Patent No. 330,839, dated November 17, 1885.

Application filed June 26, 1885. Serial No. 169,801. (No model.)

To all whom it may concern:

Be it known that I, GEORGE W. KNAPP, a citizen of the United States, residing at Baltimore, in the State of Maryland, have invented certain new and useful Improvements 5 in Cherry-Seeders Machines, of which the following is a specification.

My invention relates to a machine for removing the seeds from cherries; and it consists 10 in certain novel parts, combinations of parts, and features of construction in that class of cherry-seeders which employ a hollow cylinder provided with sockets to receive the cherries.

15 The invention is illustrated in the accompanying drawings, in which Figure 1 is a side elevation of the machine. Fig. 2 is a vertical section showing one seed-punch, one socket in the cylinder, and one cherry-holder in the 20 position said parts occupy just after removing the seed from a cherry. Fig. 3 shows the pawl-hook and parts which move it. Fig. 4 is a front elevation of the machine. Fig. 5 is 25 a vertical elevation of the machine on the line $y-y$ of Fig. 4. Fig. 6 is a vertical section showing one cherry-holder and a seed-punch, both in the position they occupy before acting 30 on a cherry. This figure also shows an end view showing the same parts as seen from a transverse direction. Fig. 7 is also a sectional view 35 showing the same parts as seen from a longitudinal section of the machine on the line $z-z$ of Figs. 1 and 5.

The letter A designates the sides of the 35 frame; A', the stand on which the machine is supported; B, the hopper which receives the cherries to be seeded; C, the hollow cylinder provided with sockets a for receiving and holding cherries while the seeds are punched 40 out. The main shaft D is driven by a pulley, D', which may be some one of the well-known patented clutch-pulleys, and operated by means of a collar, 1, on the shaft, and provided with an arm, 2, connecting with the clutch 45 part of the pulley. A lever, 3, pivoted at 4, serves to shift or slide the collar, and thereby start and stop the machine. A shaft, E, turns in bearings in the sides of the frame, and has position above the main shaft. It carries near 50 each end a gear-wheel, f, with which pinions f' on the main shaft engage. The hollow cyl-

inder C has its ends b projecting through openings c in the sides of the frame, and preferably rests on rollers c' , attached to the frame, and turns thereon like a shaft. The ends 55 of the hollow cylinder are open, and each end projects somewhat beyond its bearing and is provided with ratchet-teeth, d. (See Fig. 1.) The dimensions of the sockets a , are such as to adapt them to receive a large-size cherry; 60 but they are suited likewise for small cherries, and in the bottom of each socket is a hole, e, leading to the interior of the cylinder. This hole is for the passage of the cherry-seed. A series or a number of the sockets a are arranged 65 in a row lengthwise of the cylinder, and there are a number of these rows. Each side A of the frame has a vertical slot, 5, and the ends 6 of a cross-bar, F, occupy these slots, and said cross-bar reciprocates vertically. The cross-bar has 70 two laterally-projecting flanges, 7, one above and the other below, which extend its entire length. The lower flange 7 has a number of holes, g, each of which is occupied loosely by a cherry-holder, h, which has movement up 75 and down in the said hole. The cherry-holder is tubular, (see Figs. 2, 5, and 6,) and its lower end is reamed out to form a concave socket, h', which is designed to set down on a cherry that may be in one of the sockets a of the cylinder. 80 The cherry-holder is provided with this concave socket h' in its lower end to adapt it to center the cherry (which is seated loosely in the socket a) directly over the hole e in the bottom. By so doing the punch will not miss 85 the seed. The upper end of the holder has a rim-flange, h'', which sets on the lower flange 7 of the cross-bar, and thereby sustains the holder. The seed-punches i are fixed or rigidly attached to the upper flange 7 of the cross-bar, and each projects down through one of the tubular holders h . Instead of a cross-bar with two flanges, two cross-bars may be used. The lower end of the seed-punch may be made 90 of any suitable shape adapted to penetrate the cherry, and also take effect on the seed. In the present instance this punch has four parallel ribs or flanges, i', centrally united, and at the end these parallel ribs are center-reamed, so as to form a concave punch end, i'', 95 by which shape, when the cherry is penetrat-ed, it will not be possible for the seed to slip 100

to one side and avoid the punch end. The tubular cherry-holder *h*, it will be seen, has movement up and down on the seed-punch *i*, and a spiral spring, *k*, about the upper part 5 of the seed-punch, bears on top of the cherry-holder and serves to keep the latter normally down. If the cherry-holders *h* be sufficiently heavy, the springs *k* may be dispensed with. When a cherry is in one of the sockets *a* of 10 the cylinder, the descent of the cross-bar *F* brings the end of the cherry-holder *h* (see Fig. 2) down on the cherry. As the cross-bar continues to descend, the holder remains stationary, the spiral spring *k* yields, and the punch 15 *i* passes through the cherry and forces the seed through the hole *e* in the bottom of the socket, whereupon the seed is knocked from the end of the punch by the device herein-after described. The cross-bar then begins 20 its upward movement, and thereby the punch *i* is drawn from the cherry, and while it is being withdrawn the cherry-holder *h* remains seated on the cherry, and thus serves to retain the latter in the socket *a*. When, by the con- 25 tinued ascent of the cross-bar, its lower flange 7 comes up against the rim-flange *h*² of the cherry-holder, the latter will be lifted from the cherry, and then the cylinder makes a partial turn to bring the next series or row 30 of sockets *a* in position below the punches. The cross-bar *F* is made to reciprocate vertically by two levers, one of which is pivoted at each side *A* of the frame. The pivots are designated by 8, and one end or one arm, *G*, of 35 each lever is on the outer side of the frame, and is attached to a wrist-pin, 9, at each end of the cross-bar. The other ends, *G'*, of the levers are on the inner side of the frame *A*, and each is attached to a rod, 10, of an eccentric, *H*, 40 (see Figs. 4 and 5,) two of which are on the shaft *E*. As this shaft revolves, the eccentric rods have an up and down movement, and consequently the levers *G G'* impart a vertical reciprocating motion to the cross-bar which 45 carries the punches. This construction and arrangement of the levers *G G'* is of advantage in enabling the machine to be more compact. The hollow cylinder *C* revolves by an intermittent movement, which is produced 50 (see Figs. 1 and 4) by a pawl or hook, *l*, at each end of the machine engaging with the ratchet-teeth *d* on the ends of the cylinder. Each pawl or hook is attached to the upper end of 55 an upright arm, *m*, pivoted at *m'* to the sides of the frame. A cam, *l'*, is on the end of the shaft *E*, just back of the bevel-wheel *q'*. This cam throws the pivoted arm *m*, and thereby draws the pawl-hook *l*, and imparts movement to the hollow cylinder *C*. A spring, *l''*, brings 60 the pivoted arm *m* back again, and places the pawl-hook *l* in position to engage with the next ratchet-tooth *d*.

The device heretofore referred to for knocking the seeds from the ends of the punches is 65 shown in Figs. 1, 5, and 8. It consists of a rod or rock-shaft, 11, extending through the hollow cylinder, and having at each end a suit-

able bearing, 12, which supports it. A strip, 13, of wood, sheet metal, or vulcanized rubber, extends along the rock-shaft 11, and, as seen 70 in Figs. 5 and 8, one edge of said strip touches or is in contact with the interior surface of the cylinder at one side or in front of the uppermost series of holes *e*, where the seed-punches come through. This strip 13 constitutes the 75 seed-knocker. Each end of the rock-shaft 11 has a short arm, 14, (see Figs. 1 and 8,) provided with a slot, and a pin, 15, projecting from the pawl or hook *l*, occupies said slot. It will be seen that when the pawl or hook *l* moves 80 back to engage with a ratchet-tooth *d* it will, by acting on the short arm, 14, throw the rock-shaft, thereby causing the strip 13 to sweep cross-wise of the uppermost series of holes *e*, and knocking the cherry-seeds, which, by adhering 85 to the ends of the punches *i*, may be protruding below said holes. When the pawl or hook *l* moves forward to partly turn the cylinder and bring the next series of sockets *a* below the punches, it will at the same time throw the 90 rock-shaft 11 and bring the strip 13 to its first position. When the seeds are thus knocked from the ends of the punches, they fall upon an endless belt or seed-carrier, *n*, which is mounted on four rollers, *n'*, as shown particularly in 95 Fig. 8, and one portion of which has a horizontal position just below the seed-knocker, and extends through the hollow cylinder. This endless belt travels, as indicated by the darts, from one side of the machine to the other, and 100 carries the seeds which are dropped upon it and delivers them into an inclined spout, *o*, at one side, from which they discharge into any receptacle that may be placed for them.

As shown in Figs. 1, 5, and 8, the belt *n* 105 has at each of its edges, at that portion which extends through the cylinder, a stationary upright side or guard, *o'*. These upright sides are made of sheet metal, and serve to prevent the seeds from falling off the belt. The upright 110 sides *o'* may be part of a trough through which the endless belt travels. The upright sides *o'* project from one end of the cylinder and unite with the upper part of the inclined spout *o*.

To facilitate the delivery of the seeds which 115 are upon the belt into the inclined spout, a roller, *p*, is mounted directly below the upper roller *n'* at one side of the machine. The belt, therefore, at this point passes over the front of the roller *n'*, then down under it, and 120 then over the back of the said lower roller, *p*, this arrangement enabling the upper end of the inclined spout to take a position squarely against that part of the belt *n* which passes over the front of the roller *n'*. 125

The endless belt is moved by the following described mechanism: The upper roller *n'* is mounted on a shaft, *n''*, which has a bevel-pinion, *q*, gearing with a similar pinion, *q'*, on the end of shaft *E*, and the lower roller *n'* 130 is mounted on a shaft, *n''*. Each of the roller-shafts has a pulley, *r*, and a drive-chain, *r'*, connects the two pulleys. The roller *p* is on a shaft provided with a gear-wheel, *p'*, which

engages with a wheel, p^2 , on the upper roller-shaft, n^2 .

In the operation of the machine the seeded cherries remain in the sockets a of the cylinder until it has turned a one-quarter, or a little more than one-quarter, of a revolution, at which point most of the cherries will drop out of the sockets by their own gravity. As some of the cherries, however, will remain or adhere to the sockets, clearance-punches s are provided and located within the hollow cylinder to punch down through the holes e . These clearance-punches are attached to a bar, 16, which extends lengthwise through the cylinder. This bar is parallel with the cross-bar F, above the cylinder, which carries the seed-punches, and is connected therewith by two yokes, I, one at each end of the machine. The bar within the hollow cylinder, therefore, is raised and lowered with the vertical reciprocation of the cross-bar. It is altogether practicable, however, for the bar 16 to be raised and lowered without being connected with the cross-bar F. My invention, therefore, is not limited to such connection. At each downward move of the cross-bar F the clearance punch-bar 16 also moves down, and one of the punches s passes through each of the holes e that are in position below. As these clearance-punches pass from the inside of the cylinder through the holes outward, it will be seen they will force out of the sockets a any seeded cherries that may be adhering thereto. All the seeded cherries drop into the pan J below the machine. This pan has at one side a spout, J', for the removal of the seeded cherries, and a screen in the pan (indicated in Figs. 1 and 5 by broken lines 17) has an inclined position from the top edge, 18, of the pan-back to the bottom of the pan-front, where the spout is. Any pieces of stems or leaves that may be among the seeded cherries will pass through the screen, while the cherries on the inclined screen will pass out the spout.

To prevent the cherries in the hopper B from being crushed by the revolving cylinder C, an endless apron or belt, L, is provided, which travels over two rollers, and has a vertical position, as shown particularly in Fig. 5. This apron serves practically as one of the walls of the hopper, and the same constitutes the subject-matter of a claim in Letters Patent No. 255,874, granted me April 4, 1882. The rollers of the endless apron are driven by a belt or cord, t, from a pulley, t', on the main shaft D.

The mechanism comprising the operating parts to drive the shaft E, to move the cylinder C, the cross-bar F, and the seed-knocker 60 13, is duplicated, the same being at each side of the machine, thereby giving great stability to the machine and insuring it to run smoothly.

The operation, briefly stated, is as follows: Assuming the hopper contains cherries and the machine is in motion, each socket in the cylinder which is exposed in the hopper re-

ceives a cherry. The endless apron L prevents the cherries from being crushed. The punches drive the seeds through the holes in the sockets, and the knocker removes the seeds from the ends of the punches. The endless belt carries the seeds out without their coming in contact with the interior of the cylinder, and the clearance-punches below the belt removes the seeded cherries that may adhere to the sockets, and the seeded cherries drop into the pan.

It is obvious that some of the parts and combinations which constitute my invention may be used without using others thereof. It is also evident that many of the parts may be somewhat differently constructed from what is here shown without departing from the invention.

So far as concerns that part of the invention embracing the combination of the tubular cherry-holder h and the seed-punch i, projecting through the holder, it will be understood the revolving cylinder C is not essential to their operation, for they will produce a like useful result with any other form of cherry-carrier—anything provided with a socket, a, having a hole, e, in its bottom—for instance, a horizontally-moving table.

It is obvious the endless belt n might be arranged to pass and return, or move both ways through the hollow cylinder, instead of as shown. The invention of this part, therefore, is not limited to the construction shown.

Having described my invention, I claim and desire to secure by Letters Patent of the United States—

1. A cherry-seeder having in combination a reciprocating bar, a tubular cherry-holder, h, carried loosely by the said bar and capable of free movement endwise up and down and having at its lower end a concave socket, a seed-punch attached to said bar and projecting through the tubular holder, and a cherry-carrier provided with sockets each having a hole in its bottom, as set forth.

2. A cherry-seeder having in combination a reciprocating bar provided with an upper and a lower laterally-projecting flange, a cherry-holder carried loosely by the lower flange, and a seed-punch rigidly attached to the upper flange, as set forth.

3. A cherry-seeder having in combination a revolving cylinder provided with sockets a , each having a hole in its bottom, a reciprocating bar above the cylinder carrying seed-punches, a rock-shaft extending through the hollow cylinder and having each end supported in stationary bearings, and provided with a seed-knocking strip, 13, which extends along the said rock-shaft, and mechanism, substantially as described, to turn the cylinder and impart motion to the rock-shaft, as set forth.

4. A cherry-seeder having in combination a revolving cylinder having at its end ratchet-teeth d , and provided with sockets each having a hole in its bottom, a reciprocating bar

carrying seed-punches, a rock-shaft seed-knocker extending through the hollow cylinder and provided on its end with a short arm, a pawl-hook, *l*, engaged with the ratchet-teeth 5 and also connected with the said short arm of the rock-shaft, and mechanism, substantially as described, to operate the pawl-hook, as set forth.

5. A cherry-seeder having in combination 10 a revolving cylinder provided with sockets *a*, each having a hole in its bottom, a reciprocating bar carrying seed-punches, an endless belt passing through the hollow cylinder for carrying the seeds, a stationary upright side 15 or guard at each edge of the belt, and a spout at one side of the machine having its upper part united with the ends of the said upright sides, as set forth.

6. A cherry-seeder having in combination 20 a revolving cylinder provided with sockets *a*, each having a hole in its bottom, a reciprocating bar carrying seed-punches, a rock-shaft seed-knocker extending through the hollow cylinder, and an endless belt also passing 25 through the hollow cylinder, as set forth.

7. A cherry-seeder having in combination 30 a revolving cylinder provided with sockets *a*, each having a hole in its bottom, a reciprocating bar carrying seed-punches, and a bar

located within the hollow cylinder and provided with punches *s*, to pass from the inside outward for removing cherries adhering to the sockets, as set forth.

8. A cherry-seeder having in combination 35 a revolving cylinder provided with sockets *a*, each having a hole in its bottom, a reciprocating bar carrying seed-punches, a bar located within the hollow cylinder and provided with punches *s*, to pass from the inside outward for removing cherries adhering to the 40 sockets, and a yoke connecting each end of the reciprocating bar with the ends of the bar in the cylinder, as set forth.

9. A cherry-seeder having in combination 45 a revolving cylinder provided with sockets *a*, each having a hole in its bottom, a reciprocating bar carrying seed-punches, an endless belt passing through the hollow cylinder for carrying the seeds, and a bar also within the cylinder provided with punches to pass from 50 the inside outward, as set forth.

In testimony whereof I affix my signature in presence of two witnesses.

GEORGE W. KNAPP.

Witnesses:

JOHN E. MORRIS,
JNO. T. MADDOX.
